UNITED STATES PATENT OFFICE.

AARON M. WEBER, OF NEW YORK, N. Y.

DESIGN FOR A MEMBER FOR GARMENT-SUPPORTERS.

SPECIFICATION forming part of Design No. 33,687, dated December 11, 1900.

Application filed November 10, 1900. Serial No. 36,136. Term of patent 7 years.

To all whom it may concern:

Be it known that I, AARON M. WEBER, a citizen of the United States, residing at New York, in the county of New York, State of New York, have invented a certain new and original Design for a Member of a Garment-Supporter, of which the following is a description, reference being had to the accompanying drawings, and to the letters of reference marked thereon.

10 My invention relates to a new and original design for a garment-supporter member; and it consists in a plate of the shape and configuration herein shown and described.

15 In the accompanying drawings, which illustrate the invention, Figure 1 is a plan view of the plate embodying the invention, and Fig. 2 is a cross-section of the same.

In the drawings, A represents a plate substantially flat, provided with the substantially

straight slot *a*, merging into the curved transverse slot *b*, the edges of the plate adjacent to the slot being raised, as shown at *c*.

The leading feature of the design consists in the plate having the slots *a* and *b* and the raised portions adjacent thereto, (marked *c*).²⁵

Having described my invention, what I claim as new, and desire to secure by Letters Patent, is—

The design for the member of a garment-supporter, substantially as shown and described.³⁰

In testimony whereof I affix my signature in presence of two witnesses.

AARON M. WEBER.
